HYDRAULIC MACHINE.

Application filed May 29, 1922, Serial No. 564,515. Renewed July 10, 1925.

This invention relates in general to improvements in the art of converting hydraulic energy into commercial power, and relates more specifically to improvements in the construction of hydraulic machines such as hydraulic turbines and pumps.

An object of the invention is to provide an improved hydraulic machine which is simple in construction and efficient in operation. Another object of the invention is to provide an improved method of controlling the flow of liquid through an energy converting hydraulic machine. A further object of the invention is to provide an improved method of regulating hydraulic turbines. Still another object of the invention is to provide structure for more efficiently conducting liquid through a hydraulic turbine rotor, than has heretofore been possible. These and other objects and advantages of the present invention will be apparent from the following description.

It has heretofore been proposed to convert the energy of water under head into useful power, by producing a stream of the liquid, causing the stream of liquid to whirl, and by subsequently passing the whirling mass of liquid through a suitable rotor. In order to effect delivery of the whirling mass of liquid against the rotor vanes at the most efficient angle, it has heretofore been proposed to pivotally support the rotor vanes and to provide means for adjusting the vanes about their pivotal axes. It has also been customary in prior machines of this general type, to utilize various forms of gate mechanism for controlling the quantity of liquid delivered to the rotor. One of the prior gate mechanisms comprises an annular series of adjustable guide vanes capable of simultaneously throttling the inward flow and varying the degree of whirl of the liquid. Another of the prior gate mechanisms comprises a plunger gate movable axially of the rotor in order to throttle the inward flow of liquid passing to the rotor, but in this latter type of flow controlling device no means are provided for varying the degree of whirl of the entering liquid.

In energy converting installation of this type there are numerous conditions which affect the efficiency of operation. These con-

ditions are of such variable nature that it is impossible to construct a unit in accordance with the prior art, in which maximum efficiency is maintainable for all variations in operating conditions. It is desirable in order to maintain maximum efficiency and energy conversion, to vary the degree of whirl of the entering liquid independently of variations in the quantity of liquid admitted to the rotor. When varying either the degree of whirl of the entering liquid or the quantity of liquid admitted to the rotor, it is also desirable to vary the angularity of the rotor vanes. The prior gate mechanisms in which the quantity of flow and the degree of whirl are simultaneously altered, are objectionable since they decrease the degree of whirl simultaneously with an increase in the quantity of liquid admitted, such action being seldom desirable. It is ordinarily more desirable to increase the degree of whirl with an increase in the quantity of liquid admitted, the prior mechanisms being incapable of producing such result. The prior gate mechanisms in which the degree of whirl of the entering liquid cannot be varied at all, are inefficient for that reason. The prior mechanisms for varying the angularity of the rotor vanes, do not provide for proper adjustment of the whirl and quantity varying means in order to produce maximum efficiency of operation for a predetermined adjustment of the rotor vanes.

The present invention contemplates mechanism whereby the quantity of liquid admitted, the degree of whirl of the entering liquid and the angularity of the rotor vanes may be varied simultaneously and independently of each other, to produce maximum efficiency of operation of a unit under all conditions. While the invention has been illustrated as applied to a hydraulic turbine of the reaction type, it will be obvious that the principles may be readily applied to other hydraulic machines such as centrifugal pumps wherein it is desirable to accommodate or to produce varying characteristics of the discharge flow.

A clear conception of an embodiment of the invention and of the method of operating machines constructed in accordance therewith, may be had by referring to the

drawing accompanying and forming a part of this specification, in which like reference characters designate the same or similar parts in the various views.

5 Fig. 1 is a diagrammatic part sectional view of a hydraulic turbine installation embodying the improved regulating mechanism.

10 Fig. 2 is an enlarged side elevation of an axial flow turbine rotor embodying improved means for adjusting the angularity of the rotor vanes.

15 Fig. 3 is a transverse section through one of the vanes of the rotor illustrated in Fig. 2, the section being taken along the line 20 III—III of Fig. 2 looking in the direction of the arrows.

20 The hydraulic turbine installation illustrated diagrammatically in Fig. 1, comprises generally an inward flow annular inlet conduit 2, a vane free transition space 3 adapted to receive liquid from the conduit 2 and to change the direction of flow of the liquid from radial to axial, a draft tube 4 adapted to receive liquid from the transition space 3, and an axial flow impeller or rotor 7 located between the transition space 3 and the draft tube 4. The inlet conduit 2 is in open communication with a source of liquid supply and is bounded by relatively movable 25 upper and lower walls which are capable of varying the quantity of liquid admitted to the transition space 3. The lower bounding wall of the inlet conduit 2 consists of a lower stationary casing 15 and a rotary guide vane 30 actuating ring 14, while the upper bounding wall of the conduit consists of a vertically adjustable plunger gate 6 slidably mounted upon the upper stationary turbine casing 11. The upper stationary casing 11 35 is rigidly supported directly from the lower casing 15 by means of an annular series of parallel stationary pivot bolts 12, and has a downwardly extending central bearing portion 19. The lower casing 15 is firmly supported upon a suitable foundation 20 which also forms the wall of the draft tube 4. Adjustable guide vanes 5 are pivotally supported by the stationary pivot bolts 12, these 40 guide vanes 5 spanning the annular inlet conduit 2 and being adapted to vary the degree of whirl of the liquid delivered from the conduit 2 into the transition space 3 without materially affecting the quantity of flow. Each of the guide vanes 5 is provided with a downwardly projecting adjusting pin 13 extending into an adjacent radial slot 21 formed in the guide vane adjusting ring 14. The adjusting ring 14 is rotatably supported upon the periphery of the lower casing 15 and is provided with an actuating toothed segment 51 the teeth of which mesh with a pinion 50 the operation of which will be later described. In order to permit adjustment of the guide vanes 5 about their pivot bolts 12 without interfer-

ing with adjustment of the plunger gate 6 and with the continuity of the guiding walls, the plunger gate 6 is provided with rotary circular plates 10 loosely embracing the guide vanes 5. These plates 10 permit free adjustment of the guide vanes irrespective of the position of the plunger gate 6, the details of construction of these plates and the manner of attachment thereof to the plunger gate 6 being clearly shown in my copending application S. N. 527,817, filed Jan. 9, 1922, which covers novel subject-matter shown but not specifically claimed in the present application.

The inner portion of the plunger gate 6 is preferably provided with an annular conoidal deflecting or guiding wall 9 which closely approaches and is slidable along the bearing portion 19 of the stationary upper casing 11. The deflecting wall 9 is capable of changing the general direction of flow of the liquid delivered to the transition space 3, from the inlet conduit 2, from radial to axial and is of such height that it will not interfere with the rotor 7 even when the plunger gate 6 is fully closed. The transition space 3 is bounded by the deflecting wall 9, the stationary bearing portion 19 and the stationary lower casing 15, and communicates directly with the inlet side of the impeller or rotor 7. The rotor 7 located below the transition space 3 is of the high speed axial flow type and comprises a series of radiating adjustable vanes 16 pivotally associated with a central hub 17 which is rigidly attached to the lower extremity of the vertical main shaft 8. As illustrated in Figs. 2 and 3, the rotor hub 17 has a spherical outer surface and is provided with radiating pivots 22 which are preferably rigidly attached to the hub 17 and which snugly fit correspondingly shaped bores in the vanes 16. Each of the pivot pins 22 is provided with a number of annular grooves 29 adapted to receive retaining pins 28 for the purpose of preventing outward displacement of the rotor vanes 16 while permitting rotation thereof about the pivot pins 22. The upper inner portions of the vanes 16 are provided with radial pins 30 coacting with radial upright slots 31 formed in a sleeve 18 which embraces the vertical main shaft 8 and which coacts with the bore of the bearing portion 19. The lower end of the sleeve 18 is provided with an integral collar or flange, and the portion of the sleeve 18 below this collar is provided with the radial upright slots 31. The slotted portion of the sleeve 18 is enlarged and rests upon the hub 17, the outer surface of the enlarged sleeve portion constituting a continuation of the spherical outer surface of the rotor hub 17. The outer extremities of the rotor vanes 16 closely approach the interior of the stationary casing 15, the vanes 16 preferably being of

dove tail shape with the widest portion thereof located at the rotor periphery and having varying angularity throughout their lengths. While the specific manner of adjusting the rotor vanes forms an important part of the present invention, the rotor structure generally is the invention of Forrest Nagler and has been described in numerous publications. It will be obvious that the improved vane adjustment is not limited in application to this specific form of rotor and that the principles may be applied to many other types of hydraulic rotors.

15 The upper extremity of the sleeve 18 is provided with quick pitch external threads 40 coacting with similar internal threads of a vertically shiftable sleeve 41. The sleeve 41 is permitted to slide along but is prevented from rotating relatively to the shaft 8, by means of a spline 42. Rollers 44 carried by one end of the adjusting lever 53 coact with a recess 43 in the sleeve 41 and permit free rotation of the sleeve 41 with 20 the shaft 8. The opposite end of the adjusting lever 53 coacts with a pivot 45 carried by the regulating rod 37, and the medial portion of the lever 53 is provided with an adjustable pivoted fulcrum 46 which may 25 be shifted along the lever 53 with the aid of adjusting means 47.

The plunger gate 6 has upwardly extending parallel rods 27 secured to a bracket 39 which is guided by the shaft 8. A gate adjusting lever 38 having a stationary pivot intermediate its ends connects the bracket 39 with the regulating rod 37 so that vertical motion of the rod 37 is transmitted to and produces vertical adjustment of the plunger 40 gate 6. The lower extremity of the rod 37 is provided with a quick pitch external screw thread 49 which coacts with a similar quick pitch internal screw thread of the guide vane adjusting pinion 50. The portion of the rod 45 37 between the pivot 45 and the threaded portion 49 is provided with adjusting means 48 for varying the angular position of the threaded portion 49 relatively to the upper portion of the rod 37.

50 The servo-motor 23 is provided with fluid inlet and exhaust connections 25, 26 and has a regulating valve 32 adapted to control the admission and exhaust of operating fluid to and from the servo-motor. The valve 32 is connected to one end of the governor lever 34 the opposite end of which is connected to a compensating device 36 of well known construction. The governor 33 is operable from the main shaft 8 through gearing 35 and coacts with a medial portion of the lever 34.

During normal operation of the unit illustrated in Fig. 1, the plunger gate 6 may be positioned to produce admission of quantities of liquid requisite to carry the load

imposed upon the main shaft 8, and the whirl controlling and runner vanes 5, 16 should be adjusted to produce maximum efficiency of operation corresponding to the predetermined opening of the plunger gate 6. The liquid then enters the turbine rotor 7 through the inlet conduit 2 and the transition space 3. The guide vanes 5 act upon the entering liquid to produce definite whirling motion thereof in the transition space 3, the degree of whirl being dependent upon the position of adjustment of the vanes 5. The whirling streams of liquid leaving the guide vanes 5 are consolidated in the vane free transition space 3 and have their direction of flow changed from inward to axial by the deflecting wall 9, without destroying the whirling components of flow. The whirling axially advancing solid stream of liquid is delivered from the transition space 3 directly to the rotor vanes 16 which should be properly adjusted about their pivots 22 so that the stream lines of the liquid impinge against the impact surfaces of the vanes at the most efficient angle. The liquid leaving the rotor 7 retains considerable of its whirl energy and is delivered directly to the draft tube 4 wherein the remaining whirl and velocity energy is converted into pressure.

After the unit has been placed in operation, the governor 33 acting upon the regulating valve 32 of the servo-motor 23 will automatically function to vary the position of the plunger gate 6 in accordance with variations in power demand. As the plunger gate 6 is raised to increase the quantity of flow, the whirl controlling guide vanes 5 are independently adjusted to simultaneously and automatically increase the degree of whirl of the entering fluid by virtue of the threaded portion 49 of the rod 37 coacting with the pinion 50 which in turn coacts with the segment 51 of the vane adjusting ring 14. Simultaneously with upward movement of the plunger gate 6, the rotor vanes 16 are automatically tilted to increase the area of the liquid passage through the rotor 7 and to present the impact surfaces of the vanes 16 to the whirling body of water at the most effective angle, by virtue of the adjusting lever 53 and rollers 44 forming a connection between the rod 37 and the shiftable sleeve 41. As the sleeve 41 is moved along the shaft 8, the quick pitch threads 40 function to produce relative angular displacement between the simultaneously rotating shaft 8 and sleeve 18, thereby causing the rotor vanes 16 to swing about their supporting pivots 22 in a predetermined direction. As the plunger gate 6 is moved downwardly to throttle the inward flow, reverse independent adjustment of the guide vanes 5 and of the rotor vanes 16 is effected simultaneously and automatically.

While the operation of the plunger gate 6, the guide vanes 5 and the rotor vanes 16 has been illustrated herein as occurring simultaneously, it will be obvious that the various adjustments need not be simultaneous although these adjustments are preferably made independently of each other. It will also be obvious that the adjusting means 47, 48 permit independent alteration of the position of the guide vanes 5 and of the rotor vanes 16, for a predetermined position of the plunger gate 6.

It is desirable in the construction of turbine rotors capable of producing high specific speeds, to reduce the rotor diameter as much as possible without undesirably constricting the passages through the rotor. The prior devices for effecting adjustment of rotor vanes in turbines of this type, have embodied relatively complicated and cumbersome mechanism within the rotor hub, for effecting adjustment of the vanes, thereby necessitating the provision of a hub of relatively large diameter and necessarily increasing the rotor diameter beyond desirable limits. With the construction of rotor illustrated in the drawing, the mechanism for adjusting the angularity of the rotor vanes is reduced to relatively simple form and a hub, and consequently a rotor, of minimum diameter is provided. It has been found that rotor vanes 16 of sufficient transverse thickness to accommodate an internal pivot 22 rigidly attached to the hub 17, are not objectionable in rotors of this type, and that the thickening of the vanes in fact produces better efficiency. The feature of thickening the vanes to improve the operating characteristics of rotors of this type forms no part of the present invention. The vanes 16 are effectively supported and prevented from moving away from the hub 17 due to the influence of centrifugal force, by means of the annular recesses 29 in the pivot pins 22 and the transverse retaining pins 28 coacting with these recesses. The fact that none of the vane adjustment effecting mechanism need be located within the hub 17 permits reduction of the diameter of the hub 17 to a minimum, enables ready access to all parts of the adjusting mechanism and avoids obstruction to the flow of fluid through the rotor.

It will be obvious that adjustment of the gate 6, guide vanes 5 and rotor vanes 16 may be effected either automatically as illustrated, or manually, and that automatic adjustment may be effected in accordance with variations in any one or more characteristics such as changes in load, speed, or operating head. The gate 6, guide vanes 5 or the rotor vanes 16 may be automatically adjusted in response to the same or different variable characteristics and such adjustment of one element may be entirely inde-

pendent of that of the others. The desirability and the manner of effecting such adjustments of the gate 6, guide vanes 5 and rotor vanes 16 will be readily understood by those skilled in the art.

While the invention has been illustrated as applied to a vertical turbine unit, it will be apparent that the principles are applicable to horizontal units as well as to others, and that the illustration of an open flume unit should not be considered a limitation. The features of the invention are also applicable to hydraulic machines other than turbines and the details of construction of the various manipulating mechanisms which are shown diagrammatically in the drawing are capable of considerable variation without departing from the present invention.

It should be generally understood that it is not desired to limit the invention to the exact details of construction and of operation herein shown and described, for various modifications within the scope of the claims may occur to persons skilled in the art.

It is claimed and desired to secure by Letters Patent:

1. In combination, a rotor, and means for independently varying the quantity of water delivered to said rotor, the direction of flow of said water, and the area of the passages through said rotor.

2. In combination, a rotor, means for delivering a whirling stream of water to said rotor, and means for simultaneously increasing the quantity of water delivered to said rotor, the degree of whirl of said water, and for varying the area of the passages through said rotor.

3. In combination, a rotor, means for delivering a whirling stream of water to said rotor, and means for simultaneously but independently increasing the quantity of water delivered to said rotor, increasing the degree of whirl of said water, and for varying the area of the passages through said rotor.

4. In combination, a rotor, means for delivering a whirling stream of water to said rotor, and means for independently varying the quantity of water delivered to said rotor, the degree of whirl of said water, and the angularity of the vanes of said rotor.

5. In combination, a rotor, means for delivering a whirling stream of water to said rotor, and means for independently varying the quantity of water delivered to said rotor and the degree of whirl of said water, and for simultaneously varying the area of the passages between and the angularity of the vanes of said rotor.

6. In combination, a rotor, means for varying the area of the passages through said rotor, means for varying the quantity of liquid delivered to said rotor, and means for varying the direction of flow of said liquid,

said quantity and direction varying means functioning independently of each other.

7. In combination, a rotor, means for varying the angularity of the impact surfaces of the vanes of said rotor, means for varying the quantity of liquid delivered to said rotor, and means for varying the direction of flow of said liquid, said quantity and direction varying means functioning independently of each other.

8. In combination, a rotor, means for simultaneously varying the area of the passages through and the angularity of the impact faces of the vanes of said rotor, means for varying the quantity of liquid delivered to said rotor, and means for varying the direction of flow of said liquid, said quantity and direction varying means functioning independently of each other.

20 9. In combination, a rotor, means for varying the angularity of the vanes of said rotor, means for varying the quantity of liquid delivered to said rotor, and means for producing variable whirling motion of the 25 liquid admitted to said rotor, said whirl producing means functioning to increase the whirl of the liquid when the quantity of liquid delivered to said rotor is increased.

10. In combination, a rotor, means for 30 varying the quantity of liquid delivered to said rotor, adjustable means functioning independently of said quantity varying means for varying direction of flow of liquid relatively to said rotor, and means for varying 35 the angularity of the vanes of said rotor.

11. In combination, a rotor having angularly adjustable vanes, means for varying the quantity of liquid delivered to said rotor, and adjustable means functioning independently of said quantity varying means for varying the direction of flow of the liquid delivered to said rotor.

12. In combination, a rotor, conduit means for admitting liquid to said rotor, means for 45 varying the quantity of liquid passing through said conduit means, adjustable means operable independently of said quantity varying means for producing variable whirling motion of liquid passing through 50 said conduit means, and means for varying the angularity of the vanes of said rotor.

13. In combination, a rotor, means for varying the angularity of the vanes of said 55 rotor, conduit means for admitting liquid inwardly toward the axis of said rotor, means for varying the quantity of liquid flowing through said conduit means, and adjustable means within said conduit means for varying the direction of flow of the 60 liquid admitted to said rotor, said direction varying means functioning independently of said quantity varying means.

14. In combination, a rotor, means for 65 varying the angularity of the vanes of said rotor, a gate movable axially of said rotor

to vary the quantity of liquid admitted thereto, and a series of adjustable guide vanes for varying the direction of flow of the liquid admitted to said rotor, said gate functioning independently of said guide 70 vanes.

15. In combination, a rotor, means for varying the angularity of the vanes of said rotor, means for varying the quantity of fluid admitted to said rotor, means for varying the degree of whirl of liquid admitted to said rotor, and common means for effecting simultaneous and independent adjustment of said runner vanes, of said quantity varying means and of said whirl varying 80 means.

16. In combination, a casing forming a conduit, a shaft member, a sleeve member surrounding said shaft member, a vane pivotally associated with one of said members within said conduit, means for controlling the admission of water to said conduit to revolve said vane, and means responsive to variations in speed of revolution of said vane for relatively moving said members to adjust said vane about its pivot from the exterior of said conduit.

25 17. In combination, a rotary shaft, a pivot rigidly attached to said shaft, a vane journaled on said pivot, a sleeve angularly adjustable about said shaft to vary the position of said vane upon said pivot, and means associated with said pivot for preventing displacement of said vane therealong.

18. In combination, a rotary shaft having a spherical portion, a pivot rigidly attached to said shaft at said spherical portion, a vane journaled on said pivot, and a sleeve angularly adjustable about said shaft to vary the position of said vane upon said pivot.

100 19. In combination, a rotary shaft having a spherical portion, a pivot formed integral with said shaft and extending radially from said spherical portion, a dove-tail shaped vane journaled on said pivot, means for preventing displacement of said vane away from said shaft, and a sleeve angularly adjustable about said shaft to vary the angular position of said vane relatively to said pivot.

110 20. In combination, a casing forming a conduit, a shaft member, a sleeve member surrounding said shaft member, a vane pivotally associated with one of said members within said conduit, means for controlling the admission of water to said conduit to revolve said vane, and a speed governor directly operable by one of said members for relatively moving said members to adjust said vane about its pivot from the exterior of said conduit.

120 21. In combination, a casing forming a conduit, a shaft member, a sleeve member surrounding said shaft member, a plurality of vanes pivotally associated with and 125

prising a vane having an adjustable surface, a vane having an adjustable surface for guiding fluid with respect to said rotor vane, and linkage connecting said vane surfaces, 5 said linkage comprising means for effecting relative adjustment of said surfaces.

38. In a hydraulic machine, a rotor comprising an adjustable vane, an adjustable vane for conducting fluid towards said rotor 10 vane, and linkage connecting said vanes, said linkage comprising means for effecting relative adjustment of said vanes.

39. In a hydraulic machine, a rotor comprising a pivoted vane, a pivoted vane for 15 producing whirling motion of the fluid delivered to said rotor vane, and linkage connecting said vanes, said linkage comprising means for effecting relative adjustment of said vanes.

20 40. In a hydraulic machine, a rotor comprising a vane having an adjustable surface, a vane having an adjustable surface for guiding fluid with respect to said rotor vane, a speed governor for adjusting said surfaces, 25 and means for effecting relative adjustment of said surfaces.

41. In a hydraulic machine, a rotor having adjustable vanes, adjustable guide vanes for delivering water to said rotor, and linkage connecting said guide and said rotor 30

vanes, said linkage comprising means for relatively adjusting said guide and said rotor vanes.

42. In a hydraulic machine, a rotor having a plurality of pivoted vanes, a plurality 35 of pivoted guide vanes for delivering a whirling stream of water to said rotor, and linkage connecting said guide and said rotor vanes, said linkage comprising means for relatively adjusting said guide and said rotor vanes about their pivots. 40

43. In a hydraulic machine, a rotor comprising a vane having an adjustable surface, means having an adjustable surface for guiding fluid with respect to said rotor vane, a 45 speed governor for simultaneously adjusting said surfaces, and means for effecting relative adjustment of said surfaces.

44. In a hydraulic machine, a rotor comprising a vane having an adjustable surface, 50 means having an adjustable surface for conducting fluid towards said rotor vane, a speed governor, linkage connecting said governor and said surfaces, and means between said governor and said conducting surface 55 for effecting relative adjustment to said surfaces.

In testimony whereof, the signature of the inventor is affixed hereto.

WILLIAM H. LIEBER.
